UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-CARRIER MAGAZINE.

Application filed July 18, 1921. Serial No. 485,420.

To all whom it may concern:

Be it known that I, EPPA H. RYON, a citizen of the United States, residing at Waltham, in the county of Middlesex and State of Massachusetts, have invented a new and useful Weft-Carrier Magazine, of which the following is a specification.

This invention relates to certain improvements in weft carrier magazines as applied to weft replenishing looms, and has for its object the provision of a magazine of simplified construction and very reliable operation.

With this general object in view, one feature of my invention relates to changes and improvements in the slides by which the weft carriers or bobbins are supported.

A second feature relates to certain improved thread guiding devices which effectively prevent the tangling of threads from different rows or stacks of weft carriers.

Other features relate to an improved weft carrier releasing device, to an easily detachable connection for holding the supporting slides in position, and to certain arrangements and combinations of parts which will be hereinafter described and more particularly pointed out in the appended claims.

A preferred form of my invention is shown in the drawings in which—

Fig. 1 is a side elevation of a magazine embodying my improvements;

Fig. 2 is a partial rear elevation looking in the direction of the arrow 2 in Fig. 1;

Fig. 3 is a partial sectional plan view taken along the line 3—3 in Fig. 1;

Fig. 4 is a sectional rear elevation taken along the line 4—4 in Fig. 1;

Fig. 5 is a plan view of a pair of weft carrier supporting slides;

Fig. 6 is a side elevation thereof;

Fig. 7 is a detail view of the means for securing the slide fasteners, and

Fig. 8 is a partial view of a modified form of slide.

Referring to the drawings, I have shown parts of a magazine comprising an end frame 10 connected to a second end frame

11 (Fig. 4) by cross rods 12, 12^a and 13 (Fig. 2). Vertically extending flanges 14 on the frames 10 and 11 form separate vertical passages or compartments in which stacks or rows of weft carriers may be assembled.

The lowermost weft carrier of each stack rests upon a support comprising two oppositely movable slides 15 and 16. Each slide is provided with lateral projections 17 and 18. These projections are secured to the lower edge of the slide 16 and to the upper edge of the slide 15 as clearly shown in Fig. 6. Each slide is provided with a cam slot 19 through which extends a stud 20 secured in the slotted lower end of an actuating rod 21. The stud 20 is conveniently held in position by the spring clip 22 shown in side elevation in Fig. 7.

These slides, as thus far described, are similar to those shown in my prior Patent No. 1,005,321, issued October 10, 1911, but contain certain improved features of construction which I will now describe.

The inner end of the slide 16 is bent backward upon itself to the position shown in Fig. 5, thus providing a thickened end adapted to closely engage the small end of the weft carrier W as shown in Fig. 3. This construction permits the body of the slide to be left straight, as shown in Fig. 5, and also provides a widened bearing surface for the slide.

The projections 18 on the slides are each provided with a beveled edge 23 which is found to be of particular advantage in the operation of the mechanism, as the beveled edge has a cam action on the rings of the weft carrier and avoids the abrupt engagement of the ring experienced with the former square-angled projection. The projections thus slip easily under the base of the weft carriers and smooth operation of the mechanism is insured.

In Fig. 8 I have shown a slight modification in which the projections 18 are replaced by a projection 24 which is disposed at an angle to the horizontal so that it also has a wedge-like or cam action on the weft carrier rings. In either case the de-

vice avoids a direct or abrupt engagement of the weft carrier.

The operation of my improved slides is otherwise similar to that found in my prior 5 patent and it is sufficient to state that the actuator 21 is vertically reciprocated when a weft carrier transfer is indicated. Upon the upward stroke the upper projections 17 and 18 are oppositely withdrawn to permit 10 the descent of the weft carrier supported thereon while the lower projections 17 and 18 are simultaneously advanced to prevent immediate escape of the released weft carrier. As the actuator 21 thereafter descends, the upper projections move inward to normal position and the lower projections release the weft carrier supported 15 thereon.

The frame 10 is provided with vertically 20 extending slots 30 between each two rows or stacks of weft carriers and the ends of the threads on the weft carriers are drawn out through these slots to a thread holder not shown. In the operation of the loom 25 the weft carriers in one stack are often used much more rapidly than the carriers in an adjacent stack and under these circumstances the threads become badly entangled as one stack moves downward relatively to the 30 other.

To prevent such entanglement I have provided vertically disposed guide rods 31 and 32. These rods are secured at their upper ends to the frame 10 and extend downward 35 outside and adjacent the slots 30, their lower ends being free to permit the downward passage of the threads. In filling the magazine the threads from the outer stack are drawn outward around the outer face of the 40 corresponding guide rod 31 and the threads from the inner stack are drawn past the inner face. The threads are thus sufficiently separated so that entanglement thereof does not occur.

45 Referring to Figs. 1 and 2, I have shown improved devices for yieldingly supporting the tips of the bobbins or weft carriers. These devices comprise guide members 33 each mounted on parallel links 34 and 35. 50 The links 34 are pivoted at 36 on the frame 10 and the links 35 are loosely mounted on cross rods 13. Coil springs 37 encircle the rod 13, one end of the spring being secured in the hub of a link 35 and the other being 55 secured in a collar 38 by which the tension of the spring may be adjusted. An adjusting screw 39 in the link 34 acts as a stop for the weft carrier support by engagement with a shoulder 40 on the frame 10.

60 The two supports 33 are similarly constructed and are mounted to be moved apart as a weft carrier is forced downward by the transfrerer 41. Either of them may also be forced further back to the dotted line 65 position shown in Fig. 1 if a weft carrier

fails to be properly transferred and is caught by the shuttle when only partially inserted. The parallel links cause the guide plates 33 to maintain their original angular relation as they are separated.

70 My improved bobbin support is not claimed herein but forms the subject matter of a divisional application Serial No. 709,410, filed April 28, 1924.

Having thus described my invention and 75 the method of operation thereof, the advantages of my improvements will be readily apparent.

It will be further evident that changes 80 and modifications may be made in my invention within the spirit and scope thereof as set forth in the claims and I do not wish to be otherwise limited to the details herein disclosed but what I claim is:—

1. In a loom, a weft carrier magazine having 85 downwardly extending guide ways for the weft carriers, a pair of slides effective to support the lowest weft carrier in each guide-way, and means to withdraw said slides in opposite directions to release said 90 lowest weft carrier, said slides having projections to engage and support the weft carriers and certain of said projections having edges disposed at an oblique angle to the body of the slide.

2. In a loom, a weft carrier magazine having 95 downwardly extending guide-ways for the weft carriers, a pair of slides effective to support the lowest weft carrier in each guide-way, and means to withdraw said 100 slides in opposite directions to release and advance said weft carriers, said slides having projections to engage and support said weft carriers and certain of said projections each having a beveled side edge.

3. In a loom, a weft carrier magazine having 105 downwardly extending guide-ways for the weft carriers, a pair of slides effective to support the lowest weft carrier in each guide-way, and means to withdraw said 110 slides in opposite directions to release said lowest weft carrier, said slides being disposed in pairs and one slide in each pair having an end formed with a return bend to provide additional thickness thereof.

4. In a magazine, a plurality of vertical 115 weft carrier compartments disposed in pairs, said magazine having a slot for the filling threads between each two compartments and a separate guide rod for dividing the threads 120 from each slot, each rod being positioned outside and closely adjacent its slot and being supported at one end only and being freely engaged on each side thereof by the threads passing through said slot.

5. In a magazine, a plurality of vertical 125 weft carrier compartments disposed in pairs, said magazine having a slot for filling threads between each two compartments and a straight vertical rod effective to separate 130

the threads in each slot coming from each two groups of weft carriers, said rods being supported at their upper ends only and being substantially parallel to said slots and 5 closely adjacent thereto.

6. In a magazine, weft carrier supporting slides, studs extending through slots in said

slides, and segmental spring clips engaging the ends of said studs to prevent displacement thereof. 10

In testimony whereof I have hereunto affixed my signature.

EPPA H. RYON.
